(57) CLAIM

The ornamental design for a football sports wand, as shown and described.

DESCRIPTION

FIG. 1 is a front perspective view of the football sports wand of the invention;

FIG. 2 is a front elevational view of the football sports wand of FIG. 1;

FIG. 3 is a rear elevational view of the football sports wand of FIG. 1;

FIG. 4 is a cross-sectional view of the football sports wand of FIG. 1;

FIG. 5 is a side elevational view of the football sports wand of FIG. 1;

FIG. 6 is a top elevational view of the football sports wand of FIG. 1; and,

FIG. 7 is a bottom elevational view of the football sports wand of FIG. 1.

The broken lines shown in the drawings are included for the purpose of illustrating environmental structure and form no part of the claimed design.

1 Claim, 5 Drawing Sheets
